UNITED STATES PATENT OFFICE

LOUIS H. MORIN, OF NEW YORK, N. Y., ASSIGNOR, BY MESNE ASSIGNMENTS, TO
DOEHLER VENDING MACHINES, INC., A CORPORATION OF NEW YORK

COIN-CONTROLLED MECHANISM

Application filed October 5, 1927. Serial No. 224,051.

Coin controlled devices are extensively employed for rendering conveniently available to the public a wide variety of service, and the construction and manner of operation 5 of the coin controlled mechanism of such devices is to a considerable extent determined by the nature of the service to be performed. For some kinds of service, where only the slight movement of a few mechanical 10 parts is required, merely the insertion of a coin into the coin controlled mechanism is all that the customer needs to do. In cases where it is required to transmit movement and power through the coin controlled mechanism to a secondary mechanism which provides the service, for thereby operating and controlling the operation of the latter mechanism, or for storing energy therein to cause it to operate, such coin controlled devices 15 are made manually operable. In such devices a coin is inserted and then the entire device or apparatus is operated by means of a suitable handle. In some cases the handle is directly connected to the secondary or 20 service mechanism and the coin controlled mechanism is merely unlocked by means of the coin. In other cases the handle-connected parts of the coin controlled mechanism are normally free or disconnected from the parts 25 of the coin controlled mechanism which are connected to the service mechanism and are caused to be coupled or clutched thereto by the inserted coin. Often the coin itself directly forms the coupling or driving connection, and a coin controlled mechanism of 30 this type is disclosed in my copending application for patent for vending machines, Serial No. 39,442, filed June 25, 1925, which became Patent No. 1,723,948, August 6, 1929. 35 This type of coin controlled mechanism is satisfactory where only a relatively small amount of power is to be transmitted through such mechanism. However, where considerable power is to be thus transmitted, this 40 type of mechanism is undesirable for a number of reasons, important among which is that the coin which forms the coupling or driving connection is liable to be bent, or otherwise mutilated. In another type of coin 45 controlled mechanism the inserted coin is

effective to operate a coupling member or device which couples or clutches the handle-connected parts of the mechanism to the parts thereof which are connected to the secondary or service-providing mechanism, 55 and the coin controlled mechanism of my present invention belongs to this latter type.

One object of this invention is to provide a coin controlled mechanism which is particularly adapted for heavy duty. Other objects are to provide a construction which is simple, strong, durable, effective and inexpensive to manufacture. Other objects and advantages of the invention will hereinafter 60 appear.

While the embodiment of my invention disclosed herein is shown as embodied in or installed in a vending machine having a delivery mechanism of a particular kind which is operated and controlled by means of the coin controlled mechanism, it is evident that the delivery mechanism could as well be of a different kind. For example, my application for patent for article dispenser, Serial No. 391,006, filed September 7, 1929, shows this same coin controlled mechanism as employed to operate a delivery mechanism of a different construction. It is further to be understood that coin controlled mechanism according to this invention, either in the form thereof shown or with suitable modification, is well adapted to be embodied in various kinds of dispensing devices other than those commonly known as vending machines and, in fact, may be embodied in a substantially wide variety of service-providing devices to advantage. It may be employed, not only to deliver or dispense packages, as shown, but also may be employed for rendering an entirely different form of service. For example, a suitably modified embodiment of this invention has been employed to effect the dispensing or vending of electric current, and forms the subject of my copending application for patent Serial No. 224,052, filed October 5, 1927.

In carrying out this invention, some of the features disclosed and claimed in my above noted prior Patent No. 1,723,948, have been

retained, while other features have been altered and further features have been incorporated. For example, the construction of the coin carrier and its immediate adjuncts is substantially the same as in this earlier patent, while the magnet feature thereof is claimed in my copending divisional application Serial No. 133,615, filed September 4, 1926, which became Patent No. 1,657,836, 5 January 31, 1928. The feature disclosed herein by which the coin carrier is locked in a position to close the coin slot against the insertion of a coin when the magazine of the delivery mechanism requires replenishing is substantially similar to that claimed in my copending application Serial No. 205,285, filed July 13, 1927, which became Patent No. 1,728,901 Sept. 17, 1929, as a division of Serial No. 64,501, filed October 24, 1925, 10 which became Patent No. 1,652,540, December 13, 1927. Also the particular delivery mechanism per se shown herein is substantially the same as that claimed in my application Serial No. 78,265, filed December 30, 15 1925, which became Patent No. 1,722,230, July 23, 1929 and which also shows substantially the same construction for closing the coin slot.

The invention includes various features of 30 construction and combinations of parts, which are set forth in the appended claims, and as will appear from the following description of one embodiment of the invention, which is illustrated in the accompanying drawings, in which:

Fig. 1 is a vertical section on the line 1—1 of Fig. 2, taken for the most part just back of the front plate and the doors, showing parts of the coin controlled mechanism and 40 of the delivery mechanism at the left and bottom in front elevation, the right side and upper parts of the vending machine being broken away;

Fig. 2 is a vertical section on the line 2—2 of Fig. 1, with some of the parts on the section line shown in side elevation;

Fig. 3 is a rear elevation of the coin controlled mechanism removed from the vending machine and with most of its connections 50 to the delivery mechanism omitted;

Fig. 4 is a reversed plan view of the same, as seen from above in Fig. 3;

Fig. 5 is a vertical section on the line 5—5 of Figs. 2 and 6 just back of the main frame plate, showing, in elevation, rear parts of the coin controlled mechanism as viewed from the front;

Fig. 6 is a transverse substantially horizontal section on the line 6—6 of Figs. 1 and 60 5, with some of the parts on the section line appearing in plan view, Figs. 5 and 6 being drawn to a somewhat larger scale than the preceding figures and being substantially the full size of the mechanism;

Fig. 7 is a reduced front view of the vend-

ing machine having the coin controlled mechanism of the present invention embodied therein, with the lower part of the machine in front elevation and with its upper part broken away in vertical section to show parts of the delivery mechanism, and also broken out to reduce its height as indicated by the two broken horizontal lines, and

Fig. 8 is a partial vertical section of the 75 upper part of the machine on the line 8—8 of Fig. 7, with some of the parts in the section line appearing in side elevation.

The delivery mechanism which is shown as operated and controlled by the coin controlled mechanism of this invention comprises a pair of laterally spaced endless vertically arranged carrier chains 1 and 2 having, respectively, carrier lugs 3 and 4 between which the ends of packages 5 (Fig. 1) are received and supported to be moved downward and delivered from the lower ends of the chains and to the outside of the machine at the front through a curved delivery chute 6. At their upper ends the carrier chains 1 and 2 run over idler sprockets 7 and 8 and at their lower ends run over similar sprockets 9 and 10 which are driving sprockets. The sprocket 9 is fixed on a shaft 11 and the sprocket 10 is fixed on a shaft 12. These shafts are coupled together for unitary rotation in opposite directions by means of a transverse shaft 13 provided at the left end with a bevel pinion 14 which is driven by a bevel pinion 15 fixed on the shaft 11, and this transverse shaft 13 is provided at its right end with a bevel pinion 16 which drives a bevel pinion 17 fixed on the shaft 12, these four bevel pinions all being of the same size.

In the vending machine shown, the lower left hand shaft 11 of the delivery mechanism, together with its pinion 15, is connected to the coin controlled mechanism by which the delivery mechanism is operated and controlled. This shaft 11 is normally locked by the coin controlled mechanism, and in the machine shown has a quarter turn clockwise rotation imparted thereto by the coin controlled mechanism at each operation of the machine, thereby to move the inner runs of the carrier chains 1 and 2 downward a step and deliver a package 5, whereupon the shaft 11 is again locked by the coin controlled mechanism, thereby locking the carrier chains against movement. The construction and manner of operation of the coin controlled mechanism shown in the drawings as one embodiment of the invention will now be described.

A spur gear 18 is fixed upon the shaft 11 and, for simplicity of manufacture, the bevel pinion 15 is formed in the same piece therewith. The gear 18 is engaged and operated by a similar gear 19, shown as of the same diameter, which is carried by a rotatable

operating member 20 and, for simplicity of construction, is formed on the periphery thereof in the same piece therewith. The rotatable member 20 is loosely journaled on a stud shaft 21 which projects rearwardly from a boss 22 which is formed on the rear of a main frame piece 23 which is mostly in the form of a vertical transverse plate. This main frame part 23 is secured in place by means of three screws 24 entering lugs 25 provided in the vending machine casing 26. An auxiliary frame piece 27 is secured to the front and upper part of the main frame piece 23 by means of a pair of screws 28 and the uppermost screw 24. The forward end of the operating shaft 11 and also the driving pinion 14 for the shaft 13 are journaled in this auxiliary frame part 27.

It may now be noted that, so far as the coin controlled mechanism is concerned, the operating shaft 11 which extends rearward from the spur gear 18 could as well be connected to some other form of delivery mechanism or to any kind of dispensing or service device which requires to be operated and controlled in substantially the same manner as the delivery mechanism shown. It might also be noted that in a slightly modified form of the invention or in a different application thereof, the two intermediary first and second connecting gears 18 and 19 might be omitted, and in such case the rotatable operating member 20 fixed directly upon an operating shaft corresponding to the shaft 11 to extend rearwardly therefrom, but the particular connecting means shown has advantages in construction and operation, as will presently more clearly appear.

Normally, the rotatable operating member 20 is positively locked against rotative movement in either direction and thereby similarly locks the carrier chains 1 and 2 against traveling movement. For this purpose, the rotatable member 20 is provided in its forward face with four abrupt faced circumferential equidistant notches or locking recesses 29. A coin operated locking lever 30 of the first order is pivoted on a pin 31 between a pair of lugs 32 on the rear face of the main frame plate 23. This lever has a locking end 33 which is normally engaged in one of the notches 29 and which projects forwardly where it is supported and guided in a slotted hole 34 through the frame plate 23, this hole being shown as continued in larger dimensions through the auxiliary frame plate 27.

A coiled expansion spring 35 housed in an opening through the main frame plate 23 seats against the auxiliary frame plate 27, and presses the adjacent locking arm of the lever 30 rearwardly to urge its locking end 33 into locking engagement with the rotatable operating member 20. The other or releasing arm of the locking lever 30 is pro-

vided with a forwardly projecting cam end 36 which is guided in a slotted hole 37 through the main frame plate 23 beyond which it projects and has an inclined cam face which terminates in an acute angle towards the adjacent end of the lever. The inclined face of this cam end 36 is to be engaged by the rear edge of a moving coin, thereby to withdraw the locking end 33 from one of the recesses 29 preparatory to the imparting of a step of rotative movement to the rotatable operating member 20.

A rocking pinion segment 38 having its toothed portion normally directed downward is loosely journaled on the rear end of the stud shaft 21 immediately adjacent to the rear face of the rotatable operating member 20. A one-way driving connection is provided between this rocking pinion segment and the rotatable member 20. For this purpose the rear end of the rotatable member 20 is provided with four peripheral pawl teeth 39, the abrupt faces of which are directed counter-clockwise when viewed from the rear, as in Fig. 3, for the clockwise rotation of this member 20, as also viewed from the rear, and for its counter-clockwise rotation when viewed from the front, as in Figs. 1 and 5. These teeth 39 are engaged by an operating pawl 40 pivoted on a stud 41 carried by a tail arm of the pinion segment 38 and pressed into engagement by a bent wire spring 42 on the pinion segment to which it is anchored at one end and is held by means of a small stud 43. In the normal position of the pinion segment 38 the end of the driving pawl 40 has some freedom or space for lost motion with the pawl teeth 39 which serves as a part of the means to assure that the rotatable member 20 is in an unlocked condition when driving power is applied thereto by the pinion segment 38.

The pinion segment 38 is engaged by the teeth of a rocking gear segment 44 which is loosely journaled on the rear reduced end of a rocking operating shaft 45 from which it is normally disconnected so as not to be operated thereby, whereby this gear segment forms an initial operating member for the above described parts through which the shaft 11 is rotated to operate the delivery mechanism shown or other suitable dispensing device. This gear segment is shown as substantially in the form of an arm which extends at an upward inclination from its journal shaft 45. For convenience of manufacture, the segmental toothed portion thereof is a separate piece secured in place by rivets 46 (see Figs. 3, 4 and 6).

The arm of the gear segment 44 normally abuts at its lower edge against a stop stud 47 which projects from the rear of the main frame plate 23. A coiled retractile return spring 48 for the gear segment is connected thereto near the outer end thereof by means

of a stud 49 from which the spring extends downward and is anchored at its lower end to a stud 50 on the end of a boss 51 which projects from the main frame plate 23. The 5 rocking operating shaft 45 extends through the main frame plate 23 and is journaled therein by means of a boss 52 formed thereon at the rear to provide a bearing.

Between its rear reduced portion on which 10 the gear segment 44 is journaled and its larger bearing portion which is journaled in the boss 52, the operating shaft 45 is shown as shouldered to form an intermediate squared portion. Between the rear 15 end of the bearing boss 52 and the gear segment 44 a rocking lever arm 53 is fixed on the rocking operating shaft 45 by means of its squared portion to be rocked thereby. This lever arm is immediately adjacent to 20 the front face of the gear segment arm 44 and normally extends substantially in the same direction. This lever arm 53 forms a normally ineffective freely idly movable driving member for the gear segment arm 25 44, from which it is normally disconnected. A normally ineffective coupling device, to be made effective by the moving coin, is provided for coupling or connecting the lever arm 53 to the gear segment arm 44 so that 30 this gear segment will then be driven by the lever arm 53 in the forward rocking movement of the latter, and the particular coupling device shown as provided for this purpose will now be described.

35 Above the rocking operating shaft 45 and parallel thereto a star wheel shaft 54 is journaled in and projects at both ends beyond a bearing 55 formed on the main frame plate 23 at the top thereof. A coin-driven star wheel 56 is fixed upon the front end of this shaft, for rotating the latter. The teeth of this star wheel have abrupt faces in the counter-clockwise direction in which it is to be rotated, the other sides or faces of these teeth 40 being inclined. One of the teeth of this star wheel, at the lower part of its periphery, is always normally positioned to be engaged by the upper edge portion of the moving coin for thereby imparting a step of rotative 45 movement to the star wheel. A second or rear star wheel 57, similar to the first or front star wheel 56 and having the same number and kind of teeth similarly arranged, is fixed upon the rear end of the shaft 54. The rear face of the lower part 50 of the rear star wheel 57 is immediately adjacent to the front face of the upper part of the gear segment 44, which is widened upwardly at this point.

60 Both of the star wheels 56 and 57 are yieldably positioned and normally thus maintained by means of a yieldable stop device. For this purpose, in the construction shown, a stop roller 58 engages between the 65 teeth of the front star wheel 56, at the left

thereof as viewed from the front in Fig. 1. This roller is journaled on a headed stud 59 which projects forwardly from the adjacent end of a slide bar or plunger 60. This plunger 60 extends towards the left from the roller 58 and is supported to slide in a guideway 61 provided in the auxiliary frame plate 27 adjacent the front face of the main frame plate 23. The bar 60 is urged towards the star wheel 56 by a coiled expansion spring 62 which at its outer end abuts against the closed end of the guideway 61 therein and at its other end engages the bottom of a bore formed in the left end of the slide bar 60. As the star wheel 56 is rotated, the inclined 70 cam faces of its teeth will push back the stop roller 58 against the tension of the plunger spring 62 which will react to position the star wheel and will be effective to impart the final part of a step of movement 75 thereto.

80 A normally ineffective coupling member is made effective by one of the teeth of the rotating rear star wheel 57 to connect the driving lever arm 53, in its forward movement, 85 to the segmental gear arm 44, thereby to cause this driving arm to impart forward rocking operating movement to this segmental gear 44 and thus, through the intermediary of the operating parts hereinbefore described, to impart a step of rotative movement to the connecting shaft 11 and correspondingly a step of traveling delivery movement to the carrier chains 1 and 2.

85 In the construction shown, this coupling member comprises a two-armed pawl 63 pivoted, by means of a headed stud 64, on the forward side of the upper part of the gear segment 44. This pawl normally extends transversely and is urged to rock in a counter-clockwise direction, as viewed from the front (Figs. 1 and 5), by a wire spring 65 engaging the pivot stud 64 and having one of its ends connected to the pawl by means of a small stud 66 while its other end is anchored to the segmental gear 44 by means of a similar stud 67 which is carried by a stop lug 68 for the pawl 63 in its spring-pressed movement.

90 This spring 65 has a tendency to move the end of the driving arm of the pawl 63 into the path of the outer end of the driving lever 53, but this arm of the pawl is normally maintained out of such path against the tension of the spring 65 by reason of the tail arm of the pawl near its end abutting against the end of a tooth of the rear star wheel 57. This star wheel thus forms an escapement or trigger device for the coupling pawl 63, so that upon a slight forward movement of the star wheel the pawl will be released, whereupon 110 its spring 65 will snap it against its stop lug 68.

95 The end of the driving arm of the coupling pawl 63 will now be directly in the path of the outer end of the forwardly moving driving 120

lever arm 53 to be engaged thereby, as will be evident from the drawings, particularly Fig. 5. By reason of the fact that the lever arm 53 which drives the gear segment 44 starts to move before the pawl-controlling star wheel 57 begins to move and is continuing to move while this star wheel is moving to release the coupling pawl 63, as will presently clearly appear, some free space or lost motion is provided between the end of the driving arm 53 and the end of the coupling pawl 63 in their normal position, as clearly appears in Figs. 3 and 5. Also this lost motion provided at this point cooperates with that above noted lost motion for the operating pawl 40 relatively to the pawl teeth 39 of the rotatable operating member 20, for assuring that this rotatable member is in an unlocked condition when driving power is applied thereto by the forwardly driven pinion segment 38.

A front frame plate 69, parallel to the main frame plate 23, is spaced therefrom by projections or bosses 70 thereon and on the auxiliary plate 27 and is secured thereto by means of screws 71. The central portion of this front plate 69 is exposed at the front of the machine (Figs. 2 and 7) and has through it a slightly inclined coin slot 72 (Figs. 6 and 7). The upper or magazine part of the casing 26 is closed by an upper front door 73 hinged to the top thereof at 74, and the lower or base part of the casing is closed by a lower door 75 provided at its bottom with a hinge 76. This lower door is cut out around the central portion of the front frame plate 69 and at its inwardly turned upper end overlaps upon the lower beaded edge portion of the upper door 73 (Fig. 2). This lower door 75 is provided with a suitable lock 77 to engage a cross bar 78 provided in the casing 26 (Fig. 2).

A normally ineffective freely idly movable rocking coin carrier 79 substantially fills the space between the frame walls 23 and 69 and is fixed upon the forward end of the operating shaft 45, so that thereby the driving lever arm 53 and the coin carrier 79 are connected together for concomitant rocking movement. At its front the coin carrier 79 is provided with a pivot stud 80 journaled in the front plate 69 in axial alignment with the operating shaft 45. The coin carrier 79 extends above and below its pivotal axis and is of substantially arcuate or segmental shape. The arcuate periphery of the coin carrier 79 at the left of its axis, as viewed from the front (Fig. 1), is provided with a limiting lug 81 which may move between upper and lower stop lugs 82 and 83 provided on the main frame plate 23 for limiting the rocking movement of the coin carrier 79 together with the operating arm 53.

At its top the coin carrier 79 is provided with a coin holding slot 84 and outwardly

from this slot it carries a coin moving finger 85 to engage substantially the center of the left side of a coin 86 (Fig. 1), the lower edge of which is seated in the slot 84. This finger 85 will pass through the hole of a washer 70 and cause it to be discarded. The coin holding slot 84 is normally in alignment with the lower portion of the coin slot 72 in the front plate 69 with the end of the finger 85 just at the left of the latter slot. The right hand inclined face of the upper stop lug 82 is substantially in alignment with the left side and upper part of the coin slot 72 and serves as a guide and support for the inserted coin 86.

A laterally curved horseshoe magnet 87 is pivoted at 88 in a notch provided in the lower stop lug 83 and is held in place by a screw pin 89. The upper spaced pole ends of the magnet arms extend at an upward inclination towards the right and normally 80 slightly overlap the upper portion of the coin slot 72. The magnet arms normally rest upon the upper stop lug 82, which is notched to receive them, as shown in Figs. 1, 2, 4 and 6, and are yieldingly pressed 90 against this lug by a spring 90 mounted on the magnet by means of a pair of pins 91 and 92 and engaging at its upper end against a lug 93 on the frame plate 23. The pins 91 and 92 also serve as journals for a pair of small lower and upper rollers 94 and 95 between the magnet arms. A cam projection 96 on the coin carrier lug 81 has its upper inclined face normally just below the lower roller 94. As the coin carrier rocks forwardly the cam projection 96 will successively engage and release the rollers 94 and 95, thereby causing a paramagnetic slug to be discarded by the magnet 87 and the coin carrier 79.

When a proper coin is pushed through the coin slot 72 its upper edge will engage the forward magnet arm to lift the ends of the magnet and as the coin passes inwardly it will be received at its upper edge between the spring-pressed magnet arms, which will position the coin so that its forward edge will be clear of the coin slot 72 in the front plate 69 when the coin is moved away from this slot by the rocking of the coin carrier 79, 100 whereby the magnet 87 also forms a coin positioning device for the inserted coin 86 (Figs. 1, 2 and 6).

A coiled retractile return spring 97 for the coin carrier 79 and driving arm 53 is anchored at one end to a lug 98 on the frame plate 23 by means of a screw 99 and at its other end is connected to the lower part of the coin carrier 79 through the intermediary of a bent or curved lever 100 located for the most part in a deep slot 101 in the coin carrier and pivoted to the lower end of the coin carrier by a pin 102, shown as a screw, the upper end of this lever normally abutting against the bottom of the slot 101. The re-

100

105

110

115

120

125

130

turn spring 97 is connected to the lever 100 below the coin carrier 79. The lower end of this lever projects to the left and has pivoted thereon, by means of a pin 103, a pair of reversible pawls 104 which are urged toward their intermediary position (Fig. 1) by a pair of small coiled retractile springs 105 connected to tails of the pawls and anchored to the pivot pin 102 of the lever 100. The upper end of the lever 100 is normally positioned just at the left of the coin holding slot 84 in the coin carrier 79 and forms a feeler for a coin in this slot.

An arcuate saw-tooth ratchet 106 is provided for the pawls 104 and is shown as secured to the front of the frame plate 23 by means of a screw 107 and is held in position on this plate by a pair of dowel pins 108 which may be formed on the ratchet. When the coin carrier 79 is rocked substantially to its full extent the pawls 104, in both forward and return movement, will wipe over the ratchet 106 and escape from the corresponding end thereof. In an idle movement of the coin carrier, when there is no coin in its slot 84, the pawls 104 may reverse on the ratchet 106 to permit the return of the coin carrier to its normal position, the upper end of the lever 100 then passing across the coin holding slot 84 as these pawls reverse. A coin in the slot 84 will prevent the reversal of the pawls 104 on the ratchet 106, thereby compelling a full forward movement of the coin carrier 79 before it can be returned to its normal position. This prevents the loss of coins in the machine. A coin box or money pan 109 (Fig. 1) is provided to receive the coins when they drop from the coin carrier slot 84 at the completion of the forward movement of the coin carrier.

The means for imparting forward rocking movement to the driving lever 53 and coin carrier 79 against the tension of their return spring 97 will now be described. A tubular pinion 110 passes through a large slotted opening in the coin carrier 79 and engages with an internally toothed arcuate rack 111 on the coin carrier. The rear end of the pinion 110 projects through and is journaled in the main frame plate 23. The forward end of this pinion 110 has a head 112 journaled in the front frame plate 69 in a bearing formed by a front boss 113 on the front of this frame plate. The outer end of this head is recessed to form the cup element of a friction clutch of the cone type, as indicated by dotted lines in Fig. 2. This cup element 112 is frictionally engaged by a cone element 114. The hub 115 of a handle knob 116 is journaled in the outer reduced bore of the bearing boss 113 and is connected to the cone element 114 for positively rotating the latter.

The hub 115 of the handle knob 116 is fixed upon the outer end of a handle shaft 117 which extends inwardly loosely through

the pinion 110 and projects for some distance beyond the rear end thereof. This rear end portion of the handle shaft 117 carries a coiled compression spring 118 which acts between the handle shaft and the inner end of the pinion 110 for maintaining the clutch elements 112 and 114 in frictional driving engagement. The forward end of this clutch spring 118 bears against the inner end of the pinion 110 through the intermediary of an interposed spacing sleeve 119 and washers 120 and 121 at the ends thereof. This spacing sleeve is employed in order to provide clearance for the driving lever arm 53 and the gear segment or operating arm 44 at their lower edges when in their normal position, as will be more particularly evident from Fig. 3. The inner end of the clutch spring 118 bears against a washer 122 and is kept under tension, which may be adjusted, by means of a nut 123 screwed on the inner end of the handle shaft 117. This friction clutch driving connection will slip noiselessly to prevent the breaking of any part of the mechanism and will always leave the handle knob 116 in an effective operating position without lost motion.

Means are provided to prevent the loss of coins in the machine when the magazine is empty. For this purpose the forwardly directed end 124 of an upstanding locking pawl 125 is projected forwardly through an aperture in the main frame plate 23 into the return path of the coin carrier lug 81, so that the coin carrier 79 in its return movement will be stopped at a sufficiently forward position that it will obstruct the coin slot 72 in the front plate 69, against the insertion of a coin. The pawl arm 125 is carried by a transverse shaft 126 journaled between a pair of lugs 127 on the back of the frame plate 23 and is pivotally held in place by means of a pair of washers 128 and screws 129. The pawl end 124 and pawl arm 125 are guided in their movement between a pair of vertically disposed lugs 130 which project from the rear of the frame plate 23. At the left of the bearing lugs 127, as viewed from the front in Figs. 1 and 5, the pawl shaft 126 is provided with a rearwardly extending crank arm 131 which terminates in a crank pin 132. The locking end 124, the pawl arm 125, its shaft 126, the crank arm 131 and its crank pin 132, all may be conveniently and inexpensively made in one piece of a suitably bent small rod, as shown.

The lower end of an upwardly extending operating link 133 is pivoted on the crank pin 132. The upper end of this link is pivoted, by means of a pin 134, to a lever arm 135 which extends inwardly towards the right normally at a downward inclination, and is pivoted on a pin shown as a bolt 136 carried by a small L-shaped bracket 137 which is attached to the adjacent side wall 130

of the casing 26. The lever arm 135 is provided with a rearwardly and downwardly turned flat feeler end 138 to abut against the adjacent end of the lowermost package 5 (Fig. 1). This lever arm 135 carries a radially projecting upstanding normally inwardly inclined display arm 139 which carries on its front face the legend "Empty". A wire spring 140, held by the pivot bolt 136, bears at its lower end against the casing wall and at its other end engages the bell crank lever formed by the two lever arms 135 and 139, with a tendency to rock these arms in a counter-clockwise direction. The upper end of the display arm 139 has thereon a limiting lug or projection 141 to abut against the adjacent casing wall when the lever arms 135 and 139 are rocked by the spring 140, the display arm 139 then assuming a vertical position.

When the feeler end 138 of the arm 135 is engaged by a package 5, this package will restrain the spring 140, whereby the operating link 133 will hold the pawl end 124 in its normally withdrawn position out of the return path of the coin carrier lug 81, as shown in the drawings, and similarly will maintain the display arm 139 at its normal inclined position shown in Fig. 1. As the packages 5 are moved downward by the carrier chains 1 and 2 these packages successively engage the feeler end 138, thus to prevent the spring 140 from acting. When the last package has been delivered, this spring acts to raise the lever arm 135 and the operating link 133, which lifts the crank arm 131, thereby to project the stop end 124 of the pawl 125 into the path of return movement of the coin carrier lug 81 while the coin carrier 79 is at its forward position. Correspondingly, the display arm 139 will be swung to its upright position. In the normal inclined position of this arm the word "Empty" will be concealed at the back of the upper door 73. When the display arm 139 is upright, then the legend "Empty" is visible through a transparent plate 142 providing a window in the door 73. If desired, this window may be extended across the front of the machine, as shown in Fig. 7, and be provided with an opaque portion 143 for concealing the legend on the display arm 139 when the latter is in its normal inclined position.

In regard to the hereinbefore described coin-actuated coupling device, it might be noted, as having a bearing on the claiming of the invention, that the coupling pawl 63, instead of, as shown, being urged towards and moved to its engaging position by its spring 65, could, by a slight modification, be constructed and arranged to be spring-pressed in its opposite direction of movement, that is, to its disengaging position. In such case, the rotating rear star wheel 57 would move the coupling pawl into its engaging

position against the tension of its spring. Such a modification of the coupling pawl could be employed without other change in the coin controlled mechanism and vending machine shown in the drawings. Such a modified construction of this coupling pawl has been successfully employed with particular utility in the coin controlled mechanism of a machine of a different kind for rendering a different service. Such a modified embodiment of this feature of the invention is disclosed in my above noted co-pending application Serial No. 224,052, filed October 5, 1927. Also obviously other details of construction of the disclosed coin controlled mechanism may be suitably modified or changed, according to particular requirements or as may be found desirable.

The operation of the coin controlled mechanism shown will now be summarized. When the coin carrier 79 carries no coin, it and the driving lever 53 may be freely idly rocked to their forward position, or to any intermediate position, and they will be idly returned to normal position by the coin carrier spring 97. The limited movement of the coin carrier 79 and driving lever 63 is completed with somewhat more than a quarter rotation of the handle knob 116. Any further or continued rotation of the handle knob will only result in the slipping of the cone clutch element 114 of the coupling clutch in the cup clutch element 112.

When the coin carrier 79 carries a coin, as shown in Fig. 1, the forward rocking of the coin carrier 79 will at first idly move the coin 86 beyond or out of alignment with the coin slot 72 in the front plate 69. As the coin carrier advances, the coin will engage, substantially at the same time, the inclined cam end 36 of the locking lever 30 and the adjacent lower tooth of the coin-driven star wheel 56. As the coin moves it now rotates the front star wheel 56 and thus also the rear star wheel 57 and at the same time is pushing back the cam end 36 of the locking lever 30. Near the beginning of its rotation, the rear star wheel 57 releases the coupling pawl 63 and substantially at the same time, or it may be a little afterwards, the rocking of the locking lever 30 by the coin withdraws its locking end 33 from one of the locking notches 29 in the rotatable operating member 20. About this time, or it may be a little previously, the end of the driving lever 53 is brought into engagement with the end of the coupling pawl 63 and initiates the forward rocking movement of the gear segment 44 which rocks the pinion segment 38. The locking lever 30 as it is rocked by the moving coin will unlock the rotatable operating member 20 before the pawl 40 of the rocking pinion segment 38 has taken up its lost motion with the adjacent pawl tooth 39 of this rotatable member 20.

A positive driving operating connection 130

is now established from the handle pinion 110 to the connecting shaft 11 by which the inner runs of the chains 1 and 2 will be moved downward a step to deliver the lowermost package 5. As soon as the operating member 20 has rotated sufficiently to move its previously engaged locking notch 29 out of register with the disengaged locking end 33 of the locking lever 30, the forwardly moving coin escapes 10 from and releases the cam end 36 of this lever, whereupon its spring 35 presses its locking end 33 against the adjacent smooth end face of the rotatable member 20, in readiness to snap into the next locking notch 29 when this 15 member 20 has completed its quarter turn step of rotation, thereby positively to arrest and lock this member, and thus also the shaft 11 and carrier chains 1 and 2.

Substantially at the time that the moving 20 coin completes its forward movement, this coin, together with the spring-pressed stop roller 58, will have repositioned the star wheels 56 and 57. As the gear segment 44 is rocked forwardly by the driving lever arm 53 25 through the intermediary of the engaged coupling pawl 63, this gear segment carries with it the coupling pawl and moves the latter bodily away from the rear star wheel 57.

When the handle knob 116 is released at 30 the completion of its forward driving movement, the coin carrier spring 97 immediately returns the coin carrier 79 and the driving lever arm 53 to their original normal position. Also, the gear segment spring 48 then 35 immediately returns the gear segment 44, together with the pinion segment 38, to their original normal position. As the rocking pinion segment 38 thus idly rotates in a reverse direction, it will reposition its pawl 40 on the pawl teeth 39 of the rotatable operating member 20, so that this pawl will then be effective for engaging the next pawl tooth at a subsequent operation.

Towards the final part of the return movement of the gear segment 44, it will bring the end of the tail arm of the coupling pawl 63 into engagement with the end of a tooth of the repositioned rear star wheel 57, which, as the gear segment continues its return movement, will rock the coupling pawl 63 against the tension of its spring 65, thus moving the coupling pawl to its normal disengaging position and resetting it for a subsequent operation. In case the coin should not free itself 45 from the coin carrier at the completion of the forward movement of the latter, then towards the beginning of the return movement of the coin carrier, the rear edge of the coin will strike the abrupt face of the cam end 36 of the locking lever 33, which will dislodge the coin from the coin holding slot 84 of the coin carrier so that the coin will then drop 50 into the money pan 109.

The illustrated embodiment of the invention 60 has operated successfully and satisfac-

tory in commercial use for operating and controlling the delivery mechanism of the vending machine shown, as well as of delivery mechanisms of a different construction, and also other service devices where a similar 70 manner of operation is required. Also the herein disclosed and claimed invention has been embodied in various variant or more or less modified forms which have proved successful and satisfactory in commercial use, 75 for fulfilling different requirements.

It will now be obvious that various modifications, a few of which have been noted, may be made in the construction shown in the drawings and above particularly described, within the principle and scope of the invention as defined in the appended claims.

I claim:

1. A coin controlled mechanism having, in 85 combination, a normally ineffective freely idly movable manually operable device including a coin carrier and a normally ineffective driving member, an axis shaft upon which the coin carrier and the driving member are fixed in axially spaced relation for unitary arcuate movement, an initial operating member normally disconnected from said manually operable device, and a normally ineffective coupling device separate from the 95 coin carrier and independently actuated by a coin moved by the coin carrier to connect the said driving member to the said operating member for causing the driving member to drive the operating member. 100

2. In a coin controlled mechanism for operating a dispensing device, the combination of a normally ineffective freely idly movable manually operable device including a coin carrier and a normally ineffective driving member connected together for concomitant movement, an initial operating member for operating the dispensing device normally disconnected from said manually operable device, a coin-driven device mounted separately 110 from the coin carrier to be independently actuated by a coin moved by the coin carrier, and a normally ineffective coupling member separate from the coin-driven device mounted upon so as to be carried by the said operating member to be moved therewith and made effective by the coin-driven device to connect the said driving member to the said operating member for causing the driving member to drive the operating member 120 through the intermediary of the coupling member. 115

3. In a coin controlled mechanism for operating a dispensing device, the combination of a normally ineffective freely idly movable driving member mounted to have only a single fixed path of movement, a freely idly movable coin carrier spaced from the driving member, means connecting the driving member and the coin carrier together for concomi- 125 130

tant movement, means including a handle for moving the driving member and the coin carrier, an initial operating member for operating the dispensing device normally disconnected from the said driving member, a coin-driven device separate from the coin carrier and independently actuated by a coin moved by the coin carrier, and a normally ineffective coupling member separate from the coin-driven device mounted upon so as to be carried by the said operating member to be moved therewith and made effective by the coin-driven device to connect the said driving member to the said operating member for causing the driving member to drive the operating member through the intermediary of the coupling member.

4. In a coin controlled mechanism for operating the delivery mechanism of a vending machine, the combination of a normally ineffective freely idly movable driving member, a freely idly movable coin carrier, means connecting the driving member and the coin carrier together for concomitant movement, means including a handle for moving the driving member and the coin carrier, an initial operating member for operating the delivery mechanism normally disconnected from the said driving member, a coin-driven device actuated by a coin moved by the coin carrier, a normally ineffective coupling member carried by the said operating member and made effective by the coin-driven device to connect the said driving member to the said operating member for causing the driving member to drive the operating member for causing the driving member to drive the operating member through the intermediary of the coupling member.

5. In a coin controlled mechanism for operating the delivery mechanism of a vending machine, the combination of a rotatable operating member for actuating the delivery mechanism, means connecting said member to the delivery mechanism to actuate the latter, an initial operating member, one-way driving connections between the initial operating member and the rotatable member for imparting limited unidirectional rotation to the rotatable member, a normally ineffective freely idly movable driving member, a freely idly movable coin carrier, means connecting the driving member and the coin carrier together for concomitant movement, means including a handle for moving the driving member and the coin carrier, a coin-driven device actuated by a coin moved by the coin carrier, and a normally ineffective coupling member carried by the said initial operating member and made effective by the coin-driven device to connect the said normally ineffective driving member to the said operating member for

causing the driving member to drive the operating member.

6. The invention defined in claim 5, in combination with a lock normally engaging said rotatable member to prevent its forward rotation and operated by the coin moved by the coin carrier to be disengaged to permit such forward rotation and to reengage and again lock said rotatable member upon the completion of its limited forward rotation.

7. In a coin controlled mechanism for operating a dispensing device, the combination of a normally ineffective freely idly movable operable device including a coin carrier and a normally ineffective driving member connected together for concomitant movement, an initial operating member for operating the dispensing device normally disconnected from said manually operable device, a coin-driven star wheel device some one of the star wheel teeth of which is always normally positioned to be engaged by a coin moved by the coin carrier to impart a step of rotative movement to the star wheel device, yieldable means for thus positioning the star wheel device, and a normally ineffective coupling member carried by the said operating member and made effective by a tooth of the coin-driven star wheel device to connect the said driving member to the said operating member for causing the driving member to drive the operating member.

8. In a coin controlled mechanism for operating a dispensing device, the combination of a normally ineffective freely idly movable rocking driving arm, a freely idly movable rocking coin carrier, means connecting the driving arm and the coin carrier together for concomitant rocking movement, stop means for limiting such rocking movement, means including a handle for rocking the driving arm and the coin carrier, a rocking arm forming an initial operating member for operating the dispensing device normally disconnected from the said driving arm, a coin-driven star wheel device comprising a pair of front and rear spaced star wheels connected together for unitary rotation and of which some one of the teeth of the front star wheel is always normally in position to be engaged by a coin moved by the coin carrier to impart a one-tooth step of rotation to the star wheel device, yieldable means engaging between the teeth of one of the star wheels for thus positioning the star wheel device, and a normally ineffective coupling pawl mounted on the said operating arm and made effective by a tooth of the rotating rear star wheel so as to be engaged by the rocking driving arm for thereby causing the driving arm to impart rocking operating movement to the said operating arm.

9. The invention defined in claim 8, in which the dispensing device embodies the delivery mechanism of a vending machine, in

combination with a rotatable member forming an operating member for actuating the delivery mechanism, means connecting said member to the delivery mechanism to actuate the latter, a one-way driving connection between the said rocking operating arm and the said rotatable member for imparting limited forward rotation to the latter, and a spring-pressed positive lock normally engaging said rotatable member to prevent its rotation in either direction and to be engaged and released by the coin moved by the coin carrier to provide for such forward rotation and automatically to reengage and again positively lock the rotatable member upon the completion of its limited forward rotation.

10. In a coin controlled mechanism for operating a dispensing device, the combination of a freely idly movable rocking coin carrier, 20 stops for limiting the movement of the coin carrier, means including a handle for rocking the coin carrier, a normally ineffective driving arm axially spaced from the coin carrier, an axis shaft fixed to the coin carrier and 25 upon which said driving arm is fixed to partake of the rocking movement of the coin carrier, a star wheel some one of the teeth of which is always normally positioned to be engaged by a coin moved by the coin carrier 30 to impart a one-tooth step of rotative movement thereto, a second similar star wheel axially spaced from the coin operated star wheel, a shaft upon which both of said star wheels are fixed so as to rotate together, a yieldably 35 spring-pressed stop device engaging between the teeth of one of the star wheels thereby yieldingly to position both of the star wheels, an operating arm forming an initial operating member for operating the dispensing device pivoted to rock on an axis coaxial with 40 the coin carrier and said driving arm and located adjacent to the latter but normally disconnected therefrom, and a normally ineffective coupling pawl pivoted on the said 45 operating arm and normally maintained out of the path of movement of the said rocking driving arm and made effective by a tooth of the rotating second star wheel to move into the path of forward movement of the driving 50 arm so as to be engaged thereby and thus cause the driving arm to impart forward rocking operating movement to the said operating arm.

11. The invention defined in claim 10, in 55 which the said coupling pawl is spring-pressed towards its engaging position and is normally held out of such position by a tooth of the second star wheel which when it is moved forward releases the pawl which will 60 then be moved by its spring into effective position to be engaged by the said driving arm.

12. In a coin controlled mechanism for operating the delivery mechanism of a vending 65 machine, the combination of a rocking gear

segment forming an initial operating member for the delivery mechanism, a spring for returning such segment to its normal position, a stop for limiting the return movement of the segment, a rocking pinion segment engaged and rocked by the gear segment, a rotatable member coaxial with and adjacent to the pinion segment, a one-way driving connection between the rocking pinion segment and the said rotatable member, means connecting the rotatable member to the delivery mechanism to actuate the latter, a rocking lever arm coaxial with and adjacent to the said gear segment and forming a driving member for the latter but which is normally ineffective and freely idly movable, a shaft upon which said driving lever arm is fixed and upon which said gear segment is loosely journaled, a freely idly movable rocking coin carrier axially spaced from said driving lever arm and fixed to said shaft, a return spring for the coin carrier, stops for limiting the rocking movement of the coin carrier, means including a handle for rocking the coin carrier against the tension of its spring, a normally ineffective coupling device actuated by a coin moved by the coin carrier to connect the said operating gear segment to the said driving lever arm for causing said lever arm to rock the gear segment against the tension of its spring, and a spring-pressed positive lock normally engaging said rotatable member to prevent its rotation in either direction and to be engaged and released by the coin moved by the coin carrier to provide for the rotation of the rotatable member and automatically to reengage and again positively lock the rotatable member upon the completion of the rotative movement imparted thereto.

13. The invention defined in claim 12, in which said coupling device comprises a coin-driven star wheel some one of the teeth of which is always normally positioned to be engaged by a coin moved by the coin carrier 110 to impart a one-tooth step of rotative movement thereto, a second similar star wheel adjacent to the said gear segment and in axial alignment with the coin-driven star wheel, a shaft upon which both of said star wheels are fixed so as to rotate together, a yieldably 115 spring-pressed stop device engaging between the teeth of the coin-driven star wheel thereby yieldingly to position both of the star wheels, and a normally ineffective coupling pawl pivoted on the gear segment and made effective by a tooth of the rotating second star wheel so as to move into the path of and be engaged by the said rocking lever arm for thereby causing said lever arm to rock the gear segment against the tension of its spring.

14. The invention defined in claim 12, in which the said means for connecting the said rotatable member to the delivery mechanism

comprises a first gear carried by the said rotatable member to rotate therewith, a second gear engaged and driven by the said first gear, and means including a shaft upon which said second gear is fixed for transmitting the 5 rotative movement of the said second gear to the delivery mechanism of the vending machine.

15. In a coin controlled mechanism, the combination of a freely idly movable coin carrier, a freely idly movable driving member, means including a handle for moving the driving member and the coin carrier, an initial operating member normally disconnected from the said driving member, a coin-driven device mounted separately from the coin-carrier to be engaged and operated by a coin moved by the coin carrier, and a normally ineffective coupling member separate from the coin carrier and from the coin-driven device to be made effective by the coin-driven device to connect the said operating member to the said driving member so that movement of the driving member will impart operating movement to the operating member.

16. In a coin controlled mechanism, the combination of a freely idly movable coin carrier, a freely idly movable driving member, means including a handle for moving the driving member and the coin carrier, an initial operating member normally disconnected from the said driving member, and a normally ineffective coupling device made effective by a coin moved by the coin carrier to connect the said operating member to the said driving member so that movement of the driving member will impart operating movement to the operating member, the said initial operating member being in the form of a rocking gear segment, in combination with a spring for returning such segment to its normal position, a stop for limiting the return movement of the segment, a rocking pinion segment engaged and rocked by the gear segment, a rotatable member coaxial with and adjacent to the pinion segment, a one-way driving connection between the rocking pinion segment and the said rotatable member, means for connecting the said rotatable member to the delivery mechanism of a vending machine to actuate the latter, and a spring-pressed positive lock normally engaged and released by the coin moved by the coin carrier to provide for such rotation and automatically to reengage and again positively lock the rotatable member upon the completion of its rotative movement.

17. In a coin controlled mechanism, the combination of a freely idly movable coin carrier, a freely idly movable driving member, means including a handle for moving the driving member and the coin carrier, an initial operating member normally disconnected from the said driving member, and a normally ineffective coupling device made effective by a coin moved by the coin carrier to connect the said operating member to the said driving member so that movement of the driving member will impart operating movement to the operating member, the said normally ineffective coupling device comprising a coin-driven star wheel some one of the teeth of which is always normally positioned to be engaged by a coin moved by the coin carrier to impart a one-tooth step of rotative movement thereto, a second similar star wheel adjacent to the said initial operating member and in axial alignment with the said coin-driven star wheel, a shaft upon which both of said star wheels are fixed so as to rotate together, a yieldably spring-pressed stop device engaging between the teeth of one of the star wheels thereby yieldingly to position both of the star wheels, and a normally ineffective coupling pawl pivoted on the said operating member and made effective by a tooth of the rotating second star wheel so as to be engaged by the said driving member for thereby causing the driving member to impart operating movement to the said operating member.

In witness whereof, I hereunto subscribe my signature.
